UNITED STATES PATENT OFFICE.

WALTER EDWIN FROST, OF AUBURN, MAINE, ASSIGNOR OF ONE-EIGHTH TO MOUNT-FORT ERNEST HUNT AND THREE-EIGHTHS TO WILLIAM ELWELL THURLOW, BOTH OF AUBURN, MAINE.

POLICE SIGNAL SYSTEM.

Application filed January 24, 1924. Serial No. 688,310

My invention has for its principal object to provide a simple, yet efficient signaling system, whereby a signal may be operated in proximity to the policeman's phone box on any beat, to signify that he is to call the police station.

In carrying out the above end, a further object is to provide means for turning on the signal, controlled from the police station, but to provide such a construction that the signal will remain in operation until manually turned off by the policeman called to the phone box.

A still further object is to provide an electrically operated tell-tale in the police station, by means of which the operator of the system may determine whether the signal has operated.

Another aim is to make provision for using the ordinary telephone wires from the police station to the phone box, to carry current for operating the signal.

In the preferred construction, a self-starting spring motor is employed to close a switch to bring the signal into play, and a brake is provided to normally hold said motor against operation, and in addition to providing means controlled at the police station, for releasing this brake, it is a further object to provide means controlled by the motor, for holding said brake in a released position, until said motor has gained momentum.

Yet another object is to provide novel connecting means between a shaft of the motor and the signal switch, whereby the latter will be effectively operated and said connecting means will be freed of unnecessary strain.

With the foregoing in view, the invention resides in the novel subject matter herein-after described and claimed, the description being supplemented by the accompanying drawings.

Figure 1 is a perspective view of a wire supporting pole upon which a policeman's telephone box is mounted, illustrating the signalling means in connection with said pole and box.

Figure 2 is a front elevation showing the unit of the system which is located in the police station.

Figure 3 is a sectional view on line 3-3 of Fig. 2.

Figure 4 is an elevation partly in section showing a portion of the signal-operating means which is disposed in proximity to the phone box.

Figure 5 is an elevation partly in section looking in the opposite direction from Fig. 4.

Figure 6 is an end elevation of the motor shown in Figs. 4 and 5.

Figure 7 is a diagram of the entire system.

In the drawings above briefly described, I have illustrated a pole 1 upon which telephone and electric light wires are mounted. Upon this pole, I have shown a policeman's telephone box 2, in which a receiver 3, and a transmitter 4 are located, said transmitter and receiver being connected by shunt wires 5 and 6, with two telephone wires 7 and 8 on the pole. The wire 7 has been shown in Fig. 7 as including a battery 9 and as leading to the usual call recording instrument 10 in the police station.

The construction and operation of this instrument are known and form no part of my invention. The wire 8 leads also to the police station and is in electrical connection with a contact 11 carried by a switch arm 12, said contact being normally in engagement with a stationary contact 13 from which a wire 14 leads to the instrument 10. Wires 15 and 16 shunt from the wires 7 and 14 and connect with a receiver 17 and transmitter 18 in the police station. It will be seen that the phone circuit so far described, is normally closed and that the phones at either end of the line may be used in the well known manner.

I have shown a signal light 19 mounted on an arm 20 which extends from the pole 1, and wires 21 and 22 are provided for this light, said wires being electrically connected with an ordinary pull chain snap switch 23, or with some other suitable switch, located in the upper portion of the phone box 2. The wires 21 and 22 may receive current from any desired source, such as the electric light wires 24 and 25 on the pole 1.

Below the switch 23, a spring motor 26 has been illustrated, in the phone box 2, said motor including a pair of shafts 27 and 28 which travel in the directions shown by the

arrows in the drawings. One end of the shaft 27 is shown provided with a crank arm 29 with which a link 30 is slidably and pivotally connected as indicated at 31, said link being connected by a coiled spring 32 and an insulator 33, with the pull chain 34 of the switch 23. It thus follows that when shaft 27 rotates from the position shown in Fig. 7, it pulls upon the chain 34 to operate the switch 23 and illuminate the light 19, but when the switch has been turned on, the spring 32 stretches and as soon as the arm 29 passes below center, the connection 31 will relieve some of the tension on the spring and associated parts.

It is of course understood that the shafts 27 and 28 are suitably geared together in any desired manner. Co-acting with a brake wheel 35 on the shaft 28, I have shown a spring-applied brake 36, and an electro-magnet 37 has been illustrated for releasing said brake whenever it is desired that the motor shall operate to illuminate the light 19. I prefer to provide a constant source of current supply for the magnet 37, such a source being here shown in the form of a battery 38 which may well be located in the phone box 2. Also mounted in the phone box, is a normally open switch 39 having an electro-magnet 40 by means of which it may be closed. One side of the switch 39 has been shown as connected with the battery 38, by a wire 41, while the other side of said switch is connected by a wire 42 with the magnet 37, from which a wire 43 returns to the battery 38. It thus follows that when the magnet 40 is energized, the switch 39 is closed and a circuit is completed from the battery 38 through the magnet 37 to release the brake 36 and permit starting of the motor. In order to permit the motor to gain the desired momentum, novel provision is made for holding the magnet 37 in circuit, even when the switch 39 again opens, as fully described below.

An automatic switch has been shown associated with one end of the shaft 27, said switch including a pair of stationary contacts 44 and 45 and a traveling contact 46 which is carried by said shaft 27, but is normally at an open circuit position. A wire 47 shunts from the wire 41 to the contact 45 and another wire 48 leads from the contact 44 to the wire 42. Thus, as soon as initial starting of the motor takes place, the traveling contact 46 bridges the gap between the contacts 44 and 45 and holds the magnet 37 energized until the spring motor has gained the desired amount of momentum. Thus, the brake 36 will not interfere with the attainment of such momentum, but when it is released by deenergizing of the magnet 37, is in readiness to stop the motor when the latter has made one complete revolution.

The provision for energizing the electro-

magnet 40 will now be described. A hand generator 49 is located in the police station and from this generator I have shown a wire 50 leading to a contact bar 51 which is normally spaced from a second contact 52 on the switch arm 12, which arm is provided with a single handle 53, so that when this handle is depressed, the switch 51-52 will be closed and simultaneously, the switch 11-13, will be opened. When the generator 49 is operated and the handle 53 is forced downwardly, the current travels along the wire 50, through the contacts 51 and 52, through the switch arm 12 and the wire 8, and throughout a portion of the latter's length. The current then shunts from the wire 8 through a wire 54 which leads to the magnet 40 and may well include a condenser 55, which prevents any storage batteries used in circuit therewith from discharging into the ground. If the wiring system does not have a ground, the condenser is unnecessary. From the magnet 40, a wire 56 has been shown leading to a water pipe or other ground 57, and this ground is connected by a wire 58 with the generator 49 so as to complete the circuit for the magnet 40.

I have illustrated a tell-tale bell 59 in the station house so that the operator of the system may determine when the motor has operated and the light 19 illuminates. A wire 60 has been shown extending from the wire 8 to the bell 59 and another wire 61 extends from said bell to a normally open switch 62. From this switch, a wire 63 extends to the wire 7. Extending from the wires 5 and 6 respectively, I have shown two wires 65 and 66 leading to an automatic switch on the motor 26, which switch may well include a pair of relatively movable contacts 67 and 68, one of which is in the path of the arm 29. When the motor has rotated and effected illumination of the light 19, the arm 29 closes the circuit between the contacts 67 and 68 and the current will then flow as shown by the dotted arrows in Fig. 7, that is when the switch 62 is held closed by the operator. Thus, as soon as illumination of the light 19 has been effected, the tell-tale bell 59 will ring.

If desired, I may use an electric light instead of a bell 59, or in connection with such bell, and such a light has been indicated at 69 in Fig. 7, electrically connected with the wires 60 and 63 and equipped with a switch 70 which may be considered as a substantial duplicate of the switch 62.

Whenever the operator of the system at a police station wishes to call a policeman on a certain beat, the proper handle 53 is depressed and the generator 49 is operated, it being of course understood that a plurality of the switch arms 12 are provided, so that any beat may be called when desired. The

current then flows as indicated by the heavy arrows in Fig. 7, thus energizing the magnet 40 and causing it to close the switch 39. The circuit for the magnet 37 then travels as indicated by the light full line arrows and consequently the brake 36 is released and the motor 26 starts to operate. As soon as this initial starting has taken place, the traveling contact 46 bridges the gap between the stationary contacts 44 and 45 and the magnet 37 is held energized to hold the brake 36 disengaged, until the motor has gained the necessary amount of momentum. To effect this holding of the brake 36, it is not necessary, it will be observed, to continually operate the hand generator 49, as the moment the motor has started, the circuit from the constant source of supply 38, is used to energize the magnet 37 for the proper length of time, controlled by the traveling contact 46. As the motor shaft 27 turns, the connections between it and the switch 23 are operated to illuminate the light 19 or if desired to sound some audible signal. The parts then return to normal position, with the exception of the switch 23, but the switch remains closed until the policeman opens the box and releases it.

Immediately after operating the generator 29, the operator at the police station depresses the switch 62 or 70, or both as occasion may require. Then, as soon as the motor has operated sufficiently to allow the arm 29 to force the contacts 67 and 68 into engagement with each other, the circuit for the tell-tale 59 or 69, or both, is completed and the current will then travel as shown by the dotted arrows.

As soon as the handle 53 is released, the switch arm 12 is restored to its normal posi-

tion, to complete the phone circuit, by a suitable coiled spring 71 (Fig. 3) or by other desired means.

The several switch arms 12, the contact bars 13 and 51, the generator 49, the switch 62, and the bell 59, are all by preference contained in a single compact housing 72 at the police station.

It will be seen from the foregoing that a comparatively simple, yet an exceptionally reliable and desirable system has been provided, and while excellent results may be obtained from the details disclosed, it is to be understood that this disclosure is for illustrative purposes only and that within the scope of the invention as claimed, numerous changes may be made.

I claim:

The combination with a telephone circuit from a police station to a policeman's phone box, including a normally closed switch at the station, having a handle by means of which it may be opened, of a signal in proximity to the phone box, electrical means for bringing said signal into play including a circuit formed in part by a portion of said phone circuit and a normally open switch at the station positively connected with said handle to be closed simultaneously with the opening of the first named switch, an electrical tell-tale at the police station and conductors connecting it with the phone circuit, an automatic switch at the phone box closed by operation of said signal, and conductors connecting said automatic switch with the phone circuit, whereby to operate said tell-tale when the signal is operated.

In testimony whereof I have hereunto affixed my signature.

WALTER EDWIN FROST.
